AIRPLANE BOMB HOIST

Gerald A. Peterson, Seattle, Wash., assignor to
 Boeing Aircraft Company, Seattle, Wash., a
 corporation of Washington

Application August 18, 1941, Serial No. 407,290

9 Claims. (CL 254—172)

This invention relates to hoists, such as are employed aboard an airplane or flying boat, for instance, to hoist aboard bombs or torpedoes from a lighter or barge alongside the flying boat. Such a hoist must be extremely light and compact, for reasons which are obvious in connection with airplanes, yet it must have capacity to lift loads which may vary from perhaps one hundred pounds up to as much as several thousand pounds.

It goes without saying that the handling of such loads is a delicate operation, one fraught with same danger, and the more so in that the lighter carrying the bombs will tend to rise and fall or to rock and pitch, with wave action, in a manner or with a periodicity different from that of the flying boat itself. As a result a bomb which has been or which is about to be picked up by the hoist on the airplane may rise with the barge, and relative to the airplane, faster than it is being hauled up, creating slack in the line, and then when the barge drops away this slack is taken up, and if the arrangement is such that a sudden jerk is produced, this may tear the bomb loose from its hoist line, to the obvious danger of all persons in the vicinity and to the flying boat.

Primarily it is an object of the present invention to provide a hoist for such service as has been indicated, which has associated with it or incorporated within it automatic means which, upon slackening of the cable load, will take up the slack, but which upon increase of the cable load to normal, or even to a greater value, will permit a certain amount of yielding to avoid shock, but will smoothly snub and quickly stop any downward movement of the bomb load, and hold the bomb suspended, and then quickly and immediately continue its upward movement, all without shock or jerk. In this manner the bomb will rise clear of the barge, before the latter can rise again.

More particularly it is an object of the invention to provide a hoist of this nature which operates by a combination of spring and hydraulic means, to the ends already outlined.

But a hoist which is arranged to handle 100 pound loads may not function properly with a 3600 pound load, and vice versa. Accordingly, it is a further object to provide a hoist which is readily adjustable or adaptable to the handling of such widely varying loads, thus avoiding the necessity of providing separate hoists of different capacities.

It is a further object to advance the simplicity and compactness of the hoist by a novel arrangement of the parts thereof.

It is, furthermore, an object to devise a hoist

of the general nature indicated, which is simple, compact, rugged, and light in weight.

With these and other objects in mind, as will appear as this specification progresses, my invention comprises the novel parts and the novel combination and arrangement thereof, as shown in the accompanying drawings, described in this specification, and as will be more particularly defined by the claims which terminate the same.

In the accompanying drawings I have shown the invention incorporated in a typical hoist, and have shown how the same may be installed and used, it being remembered that the drawings are illustrative only.

Figure 1 is a perspective view of an airplane and lighter, in the act of loading a bomb aboard the airplane.

Figure 2 is an axial section through the hoist on the line 2—2 of Figure 3, but with certain parts shown in elevation.

Figure 3 is a transverse section through the hoist, on the line 3—3 of Figure 2, showing parts in an intermediate position, as in picking up the load.

Figures 4 and 5 are views similar to Figure 3, showing parts in different operative positions.

Figure 6 is a vertical sectional view taken along line 6—6 of Figure 2 showing a conventional representative drive gearing arrangement.

Referring to Figure 1, the hoist, illustrated in general at H, is suitably mounted, as within the wing W, conveniently to a doorway or hatch D, through which the bombs B are to be loaded. A lighter or barge L is arranged to support the bombs, and is intended to come alongside the hull of the flying boat F in such position that the cable C, wound about the hoist drum, may pick up the bombs from the lighter and hoist them aboard the airplane. The airplane will normally be of greater mass, and have greater inertia, than the lighter L, and the lighter will tend to rise and fall with wave action, relative to the flying boat, somewhat as is indicated in dash lines in Figure 1. If the lighter starts to rise before a bomb has been lifted clear there will be a tendency for the cable C to slacken, and for it to come taut with a jerk when the lighter drops away again.

The hoist H is supported upon any suitable base, here shown as consisting of spaced standards 90 and 91, connected by a casing 9 which houses an electric motor. Rotatably supported from this base is an inner sleeve 1, which is driven from the motor 9 through gearing contained within the gear case 92, and which it is not necessary to illustrate in detail. The sleeve

1, then, may be considered the driving element of the hoist, for it is connected to the driving motor 9.

The drum 2, for compactness and convenience, is arranged concentrically about and spaced outwardly from the inner sleeve 1, and is arranged for rotation with and with relation to the sleeve. Side walls 20 and 21 may be formed integrally with either the sleeve or the drum, though as shown they are connected to the drum. They fit tightly about the sleeve, and there is thus formed between the sleeve and the drum an annular space, which is filled with a suitable fluid, as light oil.

This annular space is divided by an abutment plate 25, projecting radially inward from the drum 2, and a vane plate 15, projecting radially outward from the sleeve 1, into two chambers of mutually variable volume. For convenience these chambers are designated 3 and 4.

The vane 15 and the abutment 25 are so arranged that they block flow of fluid from one chamber to the other, except as such flow is permitted by communicating passageways or ports. Such ports are conveniently formed in one or the other, or as shown, in both the abutment 25 and the vane 15. A passageway and a corresponding snubbing check valve is illustrated at 28, in the abutment 25, arranged to block flow from the chamber 3 to the chamber 4, but to permit slow and restricted flow from the chamber 4 to the chamber 3. Similar but oppositely directed check valves 12, conveniently positioned in the vane 15, are arranged to block flow from the chamber 4 to the chamber 3, but to permit substantially unimpeded flow, at least relatively to the flow in the opposite sense past the snubbing valve 28, from the chamber 3 to the chamber 4. The snubbing valve 28 is of well-known type which opens to permit free flow in one sense, but closes automatically to restrict flow and damp movement in the opposite sense.

An adjustable regulating valve 29, accessible from the exterior of the drum 2, restricts more or less the flow through the port in abutment 25 past the snubbing valve 28 when such valve is open. The relatively free flow permissible when handling a 100 pound load would be inadequate to snub a 3600 pound load; conversely, the flow adjustment suited to the 3600 pound load would too quickly and sharply snub the lighter load. By adjustment of the valve 29 the hoist can be quickly adapted to the intended load.

To transmit driving torque from the sleeve 1 to the drum 2 I provide a yieldable or spring means, such as the coil spring 5, anchored at 51 to the sleeve 1, and at 52 to the drum 2. This spring will normally be pretensioned, and when the hoist is at rest, and there is no tension on the cable C, the spring will draw the abutment 25 into close proximity to the then stationary vane 15. Stop lugs 26 on the walls 20 and 21 limit this movement of the abutment. This position of rest is not illustrated in the drawings.

Figure 3 shows an intermediate position, which may be assumed to be the position of parts when picking up the load. Counterclockwise rotation of the sleeve 1 by the motor 9 has commenced, and the vane 15, departing from the stops 26 on the drum 2 (now held stationary by the applied load), has rotated counterclockwise, as seen in Figure 3. The cable C, wound about the drum 2, is increasingly tensioned, and the spring 5 is more tightly wound or tensioned by the rotation of sleeve 1 relative to drum 2. This relative

rotation is snubbed somewhat by the fluid, which is restricted in its passage past the snubbing valve 28 from the chamber 4 into the chamber 3. This avoids shock from too abrupt application of lift, and causes the load to be picked up smoothly. Eventually the spring 5 is tensioned in an amount equivalent to the applied static load of the bomb, whereupon (assuming no external instantaneous load-varying factors) the bomb commences to rise. The transmission is from the driving sleeve 1 through the spring 5 to the drum 2. The liquid plays no part in supporting the actual static load; it has theretofore functioned (through valves 28 and 29) to prevent too abrupt application of lift to the load, and will continue to function in this manner and also to snub the load if it is abruptly decreased, as will shortly appear.

If the applied load (static or instantaneous) becomes extremely large the vane 15 may reach the opposite side of the abutment 25, as seen in Figure 4, and stop lugs 27 limit its movement in this direction. When the vane 15 engages the stop lugs 27, as shown in Figure 4, the drive from the sleeve 1 to the drum 2 is direct.

If for any reason, as, for instance, due to uprising of the lighter L faster than the load is being hoisted, the drum tends to overrun the sleeve, due to the accumulated spring force, this is entirely permissible, whether from the position of parts shown in Figure 3 or from that shown in Figure 4. In such a case, as shown in Figure 5, slackening of the tension upon the cable C will permit the accumulated force of the spring 5 to effect overrunning of the drum with relation to the sleeve, and in this case the abutment 25, moving counterclockwise, as seen in Figure 5, quickly increases the size of the chamber 4 and decreases the size of the chamber 3. The check valves 12 open freely to permit substantially free flow from the chamber 3 into the chamber 4. However, as soon as the tendency to slacken the load on the cable is overcome, by dropping away of the lighter from beneath the bomb which it supported, there is a tendency for relative clockwise movement of the drum with relation to the sleeve, though the sleeve 2 still continues to rotate in an absolute counterclockwise sense, and the actual sense of rotation of the drum may likewise be counterclockwise. However, this tendency to reverse rotation of the drum with relation to the sleeve immediately closes the check valves 12, and tends to open the valve 28. It also tends to increase the tension in the spring 5. The restriction afforded by the snubbing valve 28, in accordance with the adjustment of the regulating valve 29, tends to snub the load and to pick it up smoothly, and eventually to transfer the static load and torque wholly to the spring, until parts resume their normal hoisting positions, and hoisting proceeds as before.

What I claim as my invention is:

1. A hoist comprising a driven inner sleeve, a spaced, concentric, and relatively rotatable outer drum, and side walls cooperating therewith to define an annular fluid-filled space, spring means secured to each of the sleeve and the drum to transmit torque from either to the other, and active to effect or permit relative rotary movement of the sleeve and drum upon change of load conditions, an abutment upon the drum and a vane upon the inner sleeve, within and dividing the annular space into two chambers of complementarily variable size, valved ports in the abutment and vane, respectively, affording relatively free communication between the chambers for

spring-urged winding-in of the drum, reacting from the inner sleeve, upon a decrease of the cable load on the drum from normal, and affording relatively restricted communication between the chambers to damp hydraulically a dynamic increase in cable loads.

2. A hoist comprising an inner sleeve, a spaced, concentric, and relatively rotatable outer drum, and side walls cooperating therewith to define an annular fluid-filled space, drive means operatively connected to the sleeve, spring means interconnecting the sleeve and drum for driving, and operable to effect winding-in of the drum upon lessening of the cable load upon the drum, and to permit relative reverse movement of the drum, with respect to the sleeve, upon increase of such cable load, an abutment upon the drum and a vane upon the sleeve, of a shape and cooperating to divide the annular space into two chambers of complementally variable size, apertures formed in the vane, and damping valves therein affording substantially unrestricted flow between said chambers in a sense to permit spring-urged winding-in of the drum upon decrease of the cable load, and an aperture formed in the abutment, and a damping valve therein affording restricted relative rotation in the opposite sense.

3. A hoist comprising a driving member and a drum, spring means reacting between the two to wind in the drum from the driving member, hydraulic means also operatively connecting the driving member and the drum, said hydraulic means including a casing defining an annular fluid-filled space, an abutment and a vane dividing the space into two chambers of mutually variable size, of the abutment and vane one being connected to move in accordance with movement of the driving member and the other in accordance with movement of the drum, valved ports in the vane and abutment affording passages for fluid from one chamber to the other, arranged and automatically operable to restrict such flow and to snub relative movement when the vane and abutment move relatively in a sense to increase the spring force, but to permit substantially unimpeded flow when, under the influence of the accumulated spring force and a lessened cable load, the vane and abutment tend to move relatively in the opposite sense, and means accessible from the exterior of the drum to adjust the flow in the snubbing sense, and thereby to vary the snubbing effect in accordance with the intended load.

4. A hoist as in claim 2, including a regulating valve cooperating with the abutment aperture to vary the effective size thereof, said regulating valve being accessible from the exterior of the drum.

5. A hoist comprising a central drive motor, an intermediate sleeve, and an outer hoist drum all disposed concentrically and in coplanar registry, means connecting one end of said sleeve to said drive motor for driving the sleeve therefrom, a coil torsion spring connecting the other end of said sleeve to said drum for rotating said drum by rotation of said sleeve, said sleeve and said drum defining an annular chamber therebetween, liquid filling such chamber, partition means dividing such chamber into mutually variable arcuate spaces, including a plate projecting inward from said drum to said sleeve through such liquid filled chamber and a plate projecting outward from said sleeve to said drum through the liquid filled chamber, and damping means including damping ports extending through said partition means for

controlled flow of liquid therethrough between such spaces to damp relative rotation of said sleeve and drum.

6. A hoist comprising a central drive motor, an intermediate sleeve, and an outer hoist drum all disposed concentrically and in coplanar registry, means connecting one end of said sleeve to said drive motor for driving the sleeve therefrom, a coil torsion spring connecting the other end of said sleeve to said drum for rotating said drum by rotation of said sleeve, said sleeve and said drum defining an annular chamber therebetween, liquid filling such chamber, partition means dividing such chamber into mutually variable arcuate spaces, including a plate projecting inward from said drum to said sleeve through such liquid filled chamber and a plate projecting outward from said sleeve to said drum through the liquid filled chamber, and damping means including damping ports extending through said partition means for controlled flow of liquid therethrough between such spaces, and valve means closable by relative rotation of said sleeve and drum stressing said coil spring to increase the restriction of such damping ports, for damping substantially such relative rotation of the sleeve and drum, and openable by relative rotation of said sleeve and drum relaxing said spring to decrease the restriction of such damping ports.

7. A hoist comprising a sleeve, a motor operable to rotate said sleeve, a hoist drum concentrically encircling said sleeve, a torsion spring interconnecting said sleeve and said drum and sufficiently stiff to transmit the entire load hoisting torque of said motor from said sleeve to said drum while strained less than 360°, said sleeve and said drum defining an annular chamber therebetween, liquid filling such chamber, partition means dividing such chamber into two mutually variable arcuate spaces, including a single plate only projecting inward from said drum to said sleeve through such liquid filled chamber, and a single plate only projecting outward from said sleeve to said drum through such liquid filled chamber, and damping means including damping ports extending through said partition means for controlled flow of liquid therethrough between such spaces, to damp relative rotation of the sleeve and drum.

8. A hoist comprising a sleeve, a motor operable to rotate said sleeve, a hoist drum concentrically encircling said sleeve, a torsion spring interconnecting said sleeve and said drum and sufficiently stiff to transmit the entire load hoisting torque of said motor from said sleeve to said drum while strained less than 360°, said sleeve and said drum defining an annular chamber therebetween, liquid filling such chamber, partition means dividing such chamber into two mutually variable arcuate spaces, including a single plate only projecting inward from said drum to said sleeve through such liquid filled chamber, and a single plate only projecting outward from said sleeve to said drum through such liquid filled chamber, and damping means including damping ports extending through said partition means for controlled flow of liquid therethrough between such spaces, and valve means movable toward closed position by relative rotation of said sleeve and drum stressing said spring to increase the restriction of such damping ports, for damping substantially such relative rotation of the sleeve and drum, and movable toward open position by relative rotation of said sleeve

and drum relaxing said spring to decrease the restriction of such damping ports.

9. A hoist comprising a central drive motor, an intermediate sleeve, and an outer hoist drum all disposed concentrically and in coplanar registry, means connecting one end of said sleeve to said drive motor for driving the sleeve therefrom, a coil torsion spring connecting the other end of said sleeve to said drum and sufficiently stiff to transmit the entire load hoisting torque of said motor from said sleeve to said drum while strained less than 360°, said sleeve and said drum defining an annular chamber therebetween, liquid filling such chamber, partition means dividing such chamber into two mutually variable arcuate spaces, including a single plate only projecting inward from said drum to said sleeve

5 through such liquid filled chamber, and a single plate only projecting outward from said sleeve to said drum through such liquid filled chamber, and damping means including damping ports extending through said partition means for controlled flow of liquid therethrough between such spaces, and valve means movable toward closed position by relative rotation of said sleeve and drum stressing said coil spring to increase the 10 restriction of such damping ports, for damping substantially such relative rotation of the sleeve and drum, and movable toward open position by relative rotation of said sleeve and drum relaxing said spring to decrease the restriction of such 15 damping ports.

GERALD A. PETERSON.
